UNITED STATES PATENT OFFICE.

WILLIS A. INGALLS, OF TROY, NEW YORK.

KNITTING-MACHINE.

1,309,288.

Specification of Letters Patent.

Patented July 8, 1919.

Application filed February 17, 1917. Serial No. 149,159.

Know all men by these presents that I, WILLIS A. INGALLS, a subject of George the Fifth, King of England, residing in Troy, county of Rensselaer, State of New York, have invented certain new and useful Improvements in Knitting-Machines, and hereby declare the following to be a full, clear, and exact description of the same, which will enable others skilled in the art to which it appertains to make and use it.

In making caps, sweaters and other articles of yarn it is frequently desired to use yarns of different colors, size or texture. The object of my invention is to provide mechanism whereby any one of three or more yarns may be used, and whereby the yarn being used may be withdrawn and either of two others inserted in its place, at such intervals and for such length of time, as may be desired. The invention consists essentially of a holder for the idle yarns, means for introducing the desired yarn into the needles and withdrawing the active yarns therefrom, together with means for introducing the yarn being withdrawn, into the holder, and for severing it.

Figure I is a plan view of a knitting machine showing my invention. Fig. II is a developed side elevation from A to A, Fig. I. Fig. III is a side elevation of the parts mounted on the vertical central shaft of the machine. Fig. IV is a sectional elevation showing the method of mounting the yarn leaders hereinafter more fully referred to. Fig. V is a plan view of a section of the needle cylinder and cam plate with part of the device shown in Fig. I removed. Fig. VI is a developed side elevation of the parts shown in Fig. V. Fig. VII is an additional plan view showing cam and lever for operating the cutter knife for severing the yarn and for operating the yarn holder. Fig. VIII is a side elevation showing method of mounting the vertically adjustable cams and operating the same by means of the pattern wheel.

1 is the frame of the machine. 1^a is the base for the cam cylinder. 2 is the dial cam plate. 3 is the vertical central shaft of the machine. 4 is an arm mounted on the shaft 3 and extending in opposite directions to a point beyond the outside of the dial cam plate and is adapted to support the yarn leaders and parts of the operating mechanism for the yarn leaders. 4 also supports the ordinary form of yarn guide 8, by means

of the screw 5, arm 6 and stem 7. Mounted in the end 4^a (Fig. II) of the arm 4 is a stem 9 which supports, and acts as a pivot for, the yarn leaders 10, 11 and 12 as shown in Figs. I, II and IV. In the end of each leader is an aperture 13 through which the yarn passes to the yarn guide 8. The leader 10 has a stem 10^a (Fig. IV) attached to the crank 16. The stem 11^a of the leader 11 is attached to crank 15 and the stem 12^a of the leader 12 is attached to crank 14. The cranks are adjustable on the stems and may be secured in any desired position by screw 14^a shown partially in dotted lines, Fig. I. Cranks 14, 15 and 16 are operated by levers 17, 18 and 19, the first two appearing in dotted lines, Fig. I. The inner ends of these levers are attached to collars 17^a, 18^a and 19^a rotatably mounted on the shaft 3 shown in Fig. III. The outer ends of the leaders 10, 11 and 12 are adapted to be swung from a point outside the cylinder needles, over the cam plate and beneath the recesses 20^a, (Fig. V) 20^b and 20^c in the plates 20^a, 20^b and 20^c. These plates are secured at their right hand ends to the cam plate by means of a block 20, and the screws 20^a, 20^b. The opposite, or left hand end of these plates are free to move vertically, but are provided with a projection 21 adapted to engage a recess 21^a (Fig. V) in the cam plate.

Mounted on the cam plate 2 is an arm 22 extending radially outward and then at right angles and forming the support for the bent levers 24, 25 and 26 all secured thereto by the screw spindle 23, (Figs. VII and II). These bent levers are designed to operate the collars 17^a, 18^a and 19^a and are connected thereto by the levers 24^b, 25^b and 26^b, (the last named not shown,) attached to the ends 24^a, 25^a and 26^a of said bent levers (Fig. I). The bent lever 24 has a projection 24^a for engaging the point 28^a of the pawl 28, (Fig. I). The bent levers 25 and 26 are identical in form and are provided with identical projections (not shown), but numbered 25^a and 26^a. The pawl 28 is rotatably mounted on pin 27 which in turn is screwed into the supporting arm 22. The faces of the bent levers 24, 25 and 26 are normally held against the stop screws 29^b, 29^a, 29^b, Fig. II, by the springs 24^c, 25^c and 26^c, which are in turn anchored to the arm 4 by the small arm 30 attached to 4 by screws 30^a (Fig. I). The screws 29^b are supported by the arm 29, which in turn is

supported on the arm 22 by screws 29^a, (Fig. II). The outer ends of the bent levers 24, 25 and 26 are adapted to engage the cam 31 shown in Fig. I. Cam 31 is mounted on the frame of the machine through the rods 32 and 32^a and is adapted to be raised and lowered to form contact with any one of bent levers 24, 25 and 26 as will be hereinafter more fully pointed out. The pawl 28 has a shoulder 28^a adapted, when the outer end of the bent lever 25 comes in contact with surface 31^b on cam 31, to come in contact with the surface 25^c on the bent lever 25, (or such other bent lever as may be in contact with the surface 31^b on the cam 31) thereby throwing the point of the pawl out of contact with the shoulder on the bent levers and releasing the bent levers, except the one so in contact. The released levers resume their contact with screws 29^b. Members 41^b and 41^c are adapted to connect the cams 31 and 41 and to hold them the required distance apart. The rod 32 projects downward through the frame of the machine and is raised and lowered through levers 32^b mounted on pin 32^c supported by frame 33 and by the lever 33^a in immediate contact with the pins 35 of the pattern wheel 34^a, (Fig. VIII). The pattern wheel 34^b is mounted on shaft 34^a in frame 34 and operated in the usual manner and the pins 35 thereon are placed according to the work to be done, as is well understood in the art.

Mounted on the vertical shaft 3 below the collar 19^a is an additional arm 36 for operating the yarn holder and the yarn cutter. The yarn holder 37 is mounted on the cam plate by the screw 37^a (Fig. VI) and is so located with reference to the ends of the plates 20^a, 20^b, 20^c that the forward end 37^b is adapted to press against the upper side of the rear end and projection 21 of said plates. Mounted on the arm 36 is a support or casing 38 (Fig. V) attached thereto by the screws 38^a and adapted to contain and support the pin 38^b and coil spring 38^c. Supported in an arm 45 (Fig. VI) projecting from the lower side of the cam plate is a screw 45^a (Fig. V) which acts as a pivot and support for the cutter knife 46. This cutter is in the form of a bell crank. Its inner surface at the forward end, 46^b, is sharp and is adapted, as it comes in contact with the sides of the cam plate, to sever the yarn. The radially extending arm of the cutter supports a pin 46^a extending upward therefrom, (Figs. V and VI,) and adapted to engage the adjustment screw 47^b in the extension 47^c of the arm 36. The screw 47^b is provided with a lock nut 47^c. Connected to the arm 36 by screw 39^a, is a bar or link 39. The outer end of this bar connects with a link 40 at the point where the roller 40^b is attached to both by the screw

40^c. The inner end of the link 40 is attached to projecting arm 22 by screw 40^d. The roller 40^b is adapted to come in contact with the inner edge of the vertically movable cam 41 when the latter is raised to the proper height by the pattern wheel mechanism. When cam 41 is in its normal (lowered) position, the bottom of the roller 40^b is above cam 41 and its top is below cam 31.

The operation of the machine is as follows: The yarn passing through the aperture 13 of the leader 12 in the position shown in Fig. V passes through the yarn guide 8 and into the needles in the usual manner. When it is desired to change from the yarn passing through leader 12 and to substitute in the place thereof the yarn passing through the eye 13 of leader 11, the screws in the pattern wheel are arranged, in accordance with common practice, to cause cam 31 to be raised to such position that the outer point of bent lever 25 will come in contact with projection 31^a of the cam 31. This, through bent lever 25, lever 25^b, rotatable collar 18^a and lever 18, will cause the forward end of the leader 11 to be moved outward across the path of the needles and cause its yarn to pass into the yarn guide and to be taken up by the needles, (the yarn passing through leader 12 still remaining on the needles,) thereby splicing the yarn passing through the eye 13 of leader 11 into the fabric. Soon after the yarn being introduced to the needles has actually been taken hold of by the needle, and before a sufficient amount of the yarn newly introduced has been drawn into the needles to take up the slack between the holder and the point at which the yarn was taken by the needle, the shoulder 41^a of the cam 41 comes in contact with the roller 40^b mounted on link 40, and, through link 39 and arm 36, withdraws the cutting surface 46^b of the cutter knife from the side of the cam plate, and at the same time releases the forward end 37^b of the dog from the holder plates releasing the end of the yarn so that it may be drawn into the fabric. The cutting surface of the cutter 46 and the forward end 37^b of the dog are normally held against the side of the cam plate and against the rearward end of the yarn holder plates respectively by the spring 39^c attached to link 39 at one end and to the cam plate at its other end. (Fig. VII). The holder and cutter are held in this released position until cam 31 is no longer in contact with bent lever 25. After the end of the yarn has been released from the holder, the point of the lever 25 comes in contact with the projection 31^b on cam 31, causing a further movement of bent lever 25 resulting in the shoulder 25^a, on bent lever 25, coming in contact with the shoulder 28^b on the pawl 28 and forcing the point 28^a 130

of the pawl out of contact with the projection 24^d on bent lever 24, whereupon the latter, owing to the pull of the spring 24^e, through the levers and rotatable collar, 5 causes the forward end of the leader 12 to swing inward between the upper surface of the cam plate and plate 20^e, withdrawing its yarn from the needles. The outer point of the bent lever 25 still remains in contact 10 with cam 31. When, however, the point of the bent lever 25 passes beyond the end of cam 31, the point 28^a of the pawl 28 catches the shoulder 25^a on bent lever 25, holding the bent lever in that position until the 15 process is repeated upon the next change of yarn. The roller 40^b remains in contact with cam 41 until such time as the parts, moving with the cam plate, recede from the point where the yarn enters the needles, and the 20 yarn is drawn under the point 37^b of the dog 37, whereupon the roller 40^b passes off the end of cam 41 and the tension of the spring 39^e causes the dog 37 to press down on the 25 yarn and the cutter 46 to strike against the side of the cam plate and sever the yarn. The yarn remains clamped in this manner until by the adjustment of the screws in the 30 pattern wheel the same process is repeated upon the introduction of the next succeeding yarn to replace the one so introduced.

While I have described a machine adapted to knit three yarns, it is apparent that by merely adding to the number of leaders, levers and cams, and increasing the capacity 35 of the holder and the number of the operative parts described, my invention may be used to knit four or more yarns, as may be desired, and I do not limit myself to a machine for knitting the number of yarns 40 shown in the drawings and described in the specification.

Having described my invention, I claim:—

1. In a circular automatic knitting machine for knitting two or more yarns, a yarn holder consisting of a plurality of plates suitably mounted and converging at their rear ends, said plates being adapted to revolve with the cam plate and to permit yarns 45 extending from the leaders to the needles to pass between them, a dog rotating with the cam plate and adapted to press against the rear end of said plates, and means for forcing said dog against the plates and for 50 releasing the dog, whereby yarns extending from the leaders and between said plates to the cutter or to the needles may be held or released, as desired.

2. In a circular automatic knitting machine for knitting two or more yarns, a yarn holder consisting of a plurality of plates suitably mounted and converging at their rear ends, said plates being adapted to revolve with the cam plate and to permit yarns 55 extending from the leaders to the needles to

pass between them, a dog rotating with the cam plate, a spring adapted to press said dog against the rear end of said plates, and pattern chain mechanism and cams operatively connected with said dog for releasing 70 the same, whereby yarns extending from the leaders and between said plates to the cutter or to the needles may be held or released, as desired.

3. In a circular automatic knitting machine for knitting two or more yarns, a yarn holder consisting of a plurality of plates suitably mounted and converging at their rear ends, said plates revolving with the cam plate and being provided with recesses to 75 admit yarns extending to said yarn leaders, a dog rotating with the cam plate and adapted to press against the rear end of said plates and means for forcing said dog against the plates and for releasing the same, 80 whereby yarns extending from the leaders and between said plates to the cutter or to the needles may be held or released, as desired.

4. In a circular automatic knitting machine for knitting two or more yarns, a yarn holder consisting of a plurality of plates suitably mounted and converging at their rear ends, said plates revolving with the cam plate and being provided with recesses to 85 admit yarns extending to said yarn leaders, a dog rotating with the cam plate, a spring adapted to press said dog against the rear end of said plates and pattern wheel mechanism and cams operatively connected with 90 said dog for releasing the same, whereby yarns extending from the leaders and between said plates to the cutter or to the needles may be held or released, as desired.

5. In a circular automatic knitting machine for knitting two or more yarns, a yarn holder consisting of a plurality of plates suitably mounted and converging at their rear ends, said plates being adapted to revolve with the cam plate and to permit 100 yarns extending from the leaders to the needles to pass between them, a dog rotating with the cam plate, a spring adapted to press said dog against the rear end of said plates, a vertically movable cam mounted on 105 the frame of the machine, pattern wheel mechanism for controlling the altitude of the vertically movable cam, a roller cam mounted on the cam plate and revolving therewith, said roller cam being adapted to engage the 110 vertically movable cam, and operatively connected with said dog, a spring, suitably mounted, to hold the roller cam in contact with the vertically movable cam, whereby 115 yarns extending from the leaders and between said plates to the cutter or to the needles may be held or released, as desired.

6. In a circular automatic knitting machine for knitting two or more yarns, a yarn holder consisting of a plurality of plates 120

suitably mounted and converging at their rear ends, said plates being adapted to revolve with the cam plate and to permit the yarns extending from the leaders to the 5 needles to pass between them, a dog rotating with the cam plate, a spring adapted to press said dog against the rear end of said plates, a cutter for severing the yarn, a vertically movable cam mounted on the frame 10 of the machine, pattern wheel mechanism for controlling the altitude of the vertically movable cam, a roller cam mounted on the cam plate and revolving therewith, said roller cam being adapted to engage the vertically 15 movable cam and operatively connected with said dog and with the cutter, a spring to hold the roller cam in contact with the vertically movable cam, whereby yarns extending from the leaders and between said plates to the cutter or to the 20 needles may be held and severed or released, as desired.

7. In a circular automatic knitting machine for knitting two or more yarns, a yarn holder consisting of a plurality of plates suitably mounted and converging at their rear ends, said plates revolving with the cam plate and being provided with recesses to admit yarns extending to the leaders, a 25 dog rotating with the cam plate, a spring adapted to press said dog against the rear end of said plates, a vertically movable cam mounted on the frame of the machine, pattern wheel mechanism for controlling the 30 altitude of the vertically movable cam, a roller cam mounted on the cam plate and revolving therewith, said roller cam being adapted to engage the vertically movable cam and operatively connected with said 35 dog, and a spring to hold the roller cam in contact with the vertically movable cam, whereby yarns extending from the leaders and between said plates to the cutter or to the 40 needles may be held or released, as desired.

8. In a circular automatic knitting machine for knitting two or more yarns, a yarn holder consisting of a plurality of plates suitably mounted and converging at their 45 rear ends, said plates revolving with the cam plate and being provided with recesses to admit yarns extending to the yarn leaders, a dog rotating with the cam plate, a spring adapted to press said dog against the rear 50 end of said plates, a cutter for severing the yarn, a vertically movable cam mounted on the frame of the machine, a pattern chain mechanism for controlling the altitude of the vertically movable cam, a roller cam 55 mounted on the cam plate and revolving therewith, said roller cam being adapted to engage the vertically movable cam and operatively connected with said dog and with the cutter, and a spring to hold the roller 60 cam in contact with the vertically movable 65

cam, whereby yarns extending from the leaders and between said plates to the cutter or to the needles may be held and severed or released, as desired.

9. A striping device for a circular automatic knitting machine consisting of the combination of a plurality of yarn leaders, pattern wheel mechanism and selective bent levers pivotally mounted and operatively connected with said leaders for controlling 70 the selection of yarn, a yarn guide, a yarn holder for holding the ends of the idle yarns and consisting of a plurality of plates suitably mounted and converging at their rear ends and having a dog adapted to press 80 against their rear ends, a yarn cutter, and means for mounting and operating said elements whereby any one of the yarns may be introduced into the yarn guide and needles, released from the holder, and used in knitting, while the idle yarns are severed and 85 their ends held clear of the needles.

10. A striping device for a circular automatic knitting machine consisting of the combination of a plurality of yarn leaders 90 mounted on an arm extending from the central shaft of the machine, pattern wheel mechanism and selective bent levers pivotally mounted and operatively connected with said leaders for controlling the selection of the yarn, a yarn guide, a yarn holder mounted on the cam plate for holding the ends of the idle yarns and consisting of a plurality of plates suitably mounted and converging at their rear ends and having 95 a dog adapted to press against their rear ends, a yarn cutter for severing the idle yarns, and means for mounting and operating said elements whereby any one of the 100 yarns may be introduced into the yarn guide and needles, released from the holder and used in knitting, while the idle yarns are severed and their ends held clear of the 105 needles.

11. A striping device for a circular automatic knitting machine consisting of the combination of a plurality of yarn leaders mounted on an arm extending from the central shaft of the machine, pattern wheel mechanism and selective bent levers pivotally mounted and operatively connected with said leaders for controlling the selection of the yarn, a yarn guide also mounted on said arm, a yarn holder mounted on the cam plate for holding the ends of the idle yarns and 115 consisting of a plurality of plates suitably mounted and converging at their rear ends and having a dog adapted to press against their rear ends, a yarn cutter mounted on the cam plate for severing the idle yarns, an arm extending from the central shaft of the machine operatively connected with said cutter and holder, pattern wheel mechanism and cams operatively connected with said 120 last mentioned arm for controlling the move- 125

ments thereof, whereby any one of the yarns may be introduced into the yarn guide and needles, released from the holder and used in knitting, while the idle yarns are severed 5 and their ends held clear of the needles.

12. A striping device for a circular automatic knitting machine consisting of the combination of a plurality of yarn leaders mounted on an arm extending from the central shaft of the machine, pattern wheel mechanism and selective bent levers pivotally mounted and operatively connected with said leaders for controlling the selection of the yarn, a yarn guide also mounted on said arm, a yarn holder mounted on the cam plate for holding the ends of the idle yarns and consisting of a plurality of plates suitably mounted and converging at their rear ends and having a dog adapted to press against their rear ends, a yarn cutter mounted on the cam plate for severing the idle yarns, an arm extending from the central shaft of the machine operatively connected with said cutter and holder, a vertically movable cam mounted on the frame of the machine, a roller cam adapted to engage said vertically movable cam and operatively connected with the last mentioned arm, pattern wheel mechanism operatively connected with said vertically movable cam for controlling the movements thereof, whereby any one of the yarns may be introduced into the yarn guide and needles, released from the holder and used in knitting, while the idle yarns are severed and their ends held clear of the needles.

13. A striping device for a circular automatic knitting machine consisting of the combination of a plurality of yarn leaders, a yarn guide, a yarn holder for holding the ends of the idle yarns, a yarn cutter, selective bent levers pivotally mounted and operatively connected with said leaders, each of said bent levers having a shoulder adapted to engage a pawl, a pawl adapted to engage the shoulders on said bent levers, said pawl having a shoulder adapted to come in contact with said bent levers at a point outside of their pivotal point, whereby the pawl is forced out of contact with the shoulder on the bent levers, pattern wheel mechanism for controlling the selection of the yarn, and means for mounting and operating said elements, whereby any one of the yarns may be introduced into the yarn guide and the needles, released from the holder, and used in knitting, while the idle yarns are severed and their ends held clear of the needles.

14. A striping device for a circular automatic knitting machine consisting of the combination of a plurality of yarn leaders mounted on an arm extending from the central shaft of the machine, pattern wheel mechanism, and selective bent levers pivotally mounted and operatively connected with

said leaders, said bent levers being adapted at their outer ends to engage a vertically movable cam, a vertically movable cam mounted in the frame of the machine for controlling the selection of the yarn, a yarn 70 guide also mounted on said arm, a yarn holder mounted on the cam plate for holding the ends of the idle yarns and consisting of a plurality of plates suitably mounted and converging at their rear ends and having 75 a dog adapted to press against their rear ends, a yarn cutter mounted on the cam plate for severing the idle yarns, an arm extending from the central shaft of the machine operatively connected with said cutter and 80 holder, pattern wheel mechanism and cams operatively connected with said last mentioned arm for controlling the movements thereof, whereby any one of the yarns may be introduced into the yarn guide and 85 needles, released from the holder and used in knitting, while the idle yarns are severed and their ends held clear of the needles.

15. A striping device for a circular automatic knitting machine consisting of the 90 combination of a plurality of yarn leaders mounted on an arm extending from the central shaft of the machine, pattern wheel mechanism and selective bent levers pivotally mounted and operatively connected 95 with said leaders, said bent levers being adapted at their outer ends to engage a vertically movable cam mounted in the frame of the machine, a vertically movable cam for controlling the selection of the yarn, a 100 yarn guide also mounted on said arm, a yarn holder mounted on the cam plate for holding the ends of the idle yarns and consisting of a plurality of plates suitably mounted 105 and converging at their rear ends and having a dog adapted to press against their rear ends, a yarn cutter mounted on the cam plate for severing the idle yarns, an arm extending from the central shaft of the machine operatively connected with said cutter 110 and holder, a vertically movable cam mounted in the frame of the machine, a roller cam operatively connected with said last mentioned arm and adapted to engage said vertically movable cam, and pattern wheel 115 mechanism, for moving said cam whereby any one of the yarns may be introduced into the yarn guide and needles, released from the holder and used in knitting, while the 120 idle yarns are severed and their ends held clear of the needles.

16. A striping device for a circular automatic knitting machine consisting of the combination of a plurality of yarn leaders mounted on an arm extending from the central shaft of the machine, selective bent levers pivotally mounted and operatively connected with said leaders, said bent levers being adapted at their outer ends to engage a vertically movable cam, a vertically mov- 130

able cam mounted in the frame of the machine for controlling the selection of the yarn, a yarn guide also mounted on said arm, a yarn holder mounted on the cam plate for holding the ends of the idle yarns, and consisting of a plurality of plates suitably mounted and converging at their rear ends and having a dog adapted to press against their rear ends, a yarn cutter mounted on the cam plate for severing the idle yarns, an arm extending from the central shaft of the machine operatively connected with said cutter and holder, a vertically movable cam mounted in the frame of the machine, a roller cam 10 operatively connected with said last mentioned arm and adapted to engage said vertically movable cam, and pattern wheel mechanism for operating the vertically movable cams controlling the bent levers and the roller cam, whereby any one of the yarns may be introduced into the yarn guide and needles, released from the holder and used in knitting, while the idle yarns are severed and their ends held clear of the needles.

15 17. A striping device for a circular automatic knitting machine consisting of the combination of a plurality of yarn leaders mounted on an arm extending from the central shaft of the machine, a yarn guide suitably mounted, a yarn holder mounted on the cam plate for holding the ends of the idle yarns, a yarn cutter, pattern wheel mechanism and selective bent levers operatively connected with said leaders for controlling the selection of the yarn, each of said bent levers having a shoulder adapted to engage a pawl, a pawl adapted to engage the shoulders on said bent levers, said pawl having a shoulder adapted to come in contact with said bent levers at a point outside of their pivotal point, whereby the pawl is forced out of contact with the shoulder on the bent levers, and means for operating said yarn holder and for mounting and operating said 20 yarn cutter, whereby any of the yarns may be released from the holder, introduced into the yarn guide and the needles and used in knitting, while the idle yarns are severed and their ends held clear of the needles.

25 18. A striping device for a circular automatic knitting machine consisting of the combination of a plurality of yarn leaders mounted on an arm extending from the central shaft, a yarn guide also mounted on said arm, a yarn holder mounted on the cam plate for holding the ends of the idle yarns, a yarn cutter, pattern wheel mechanism and selective bent levers operatively connected with

30 said leaders for controlling the selection of the yarn, each of said bent levers having a shoulder adapted to engage a pawl, a pawl adapted to engage the shoulders on said bent levers, said pawl having a shoulder adapted to come in contact with said bent levers at a point outside of their pivotal point, whereby the pawl is forced out of contact with the shoulder on the bent levers, and pattern wheel mechanism for operating the vertically movable cam, a yarn guide suitably mounted, a yarn holder mounted on the cam plate for holding the ends of the idle yarns, a yarn cutter mounted on the cam plate for severing the ends of the idle yarns, and means for operating said yarn holder and said yarn cutter, whereby any of the yarns may be introduced into the yarn guide and the needles, and released from the holder and used in knitting while the idle yarns are severed and their ends held clear of the needles.

35 19. A striping device for a circular automatic knitting machine consisting of the combination of a plurality of yarn leaders mounted on an arm extending from the central shaft of the machine, bent levers pivotally mounted on the cam plate and operatively connected at one end to said leaders and adapted at their opposite ends to engage a vertically movable cam mounted in the frame of the machine, each of said bent levers having a shoulder adapted to engage a pawl, a pawl adapted to engage the shoulders on said bent levers, said pawl having a shoulder adapted to come in contact with said bent levers at a point outside of their pivotal point, whereby the pawl is forced out of contact with the shoulder on the bent levers, pattern wheel mechanism for operating the vertically movable cam, a yarn guide suitably mounted, a yarn holder mounted on the cam plate for holding the ends of the idle yarns, a yarn cutter mounted on the cam plate for severing the ends of the idle yarns, and means for operating said yarn holder and said yarn cutter, whereby any of the yarns may be introduced into the yarn guide and the needles, and released from the holder and used in knitting while the idle yarns are severed and their ends held clear of the needles.

40 20. In witness whereof I hereunto set my hand at Cleveland, Ohio, this 10th day of February, 1917.

WILLIS A. INGALLS.

In the presence of—
 E. W. PETERS,
 E. N. CONRAD.
